Des. 207,887
Patented June 6, 1967

207,887

CLOSURE FOR A DISPLAY PACKAGE

Francis Leroy Parsisson, Florence, and Lewis James Halbertstadt, Williamsburg, Mass., assignors to Pro-Phy-Lac-Tic Brush Company, Florence, Mass., a corporation of Delaware

Continuation of design applications Ser. No. 1,076 and Ser. No. 1,077, Feb. 16, 1966. This application Nov. 21, 1966, Ser. No. 5,566

Term of patent 14 years

(Cl. D58—26)

FIG. 1 is a perspective view of a closure for a display package showing our new design, with a display package shown in broken lines for illustrative purposes;

FIG. 2 is a front elevational view;

FIG. 3 is a side elevational view;

FIG. 4 is a top plan view;

FIG. 5 is a bottom perspective view;

FIG. 6 is a perspective view of a closure for a display package showing an embodiment of our new design, with a display package shown in broken lines for illustrative purposes;

FIG. 7 is a front elevational view of the embodiment of FIG. 6;

FIG. 8 is a side elevational view of the embodiment of FIG. 6;

FIG. 9 is a top plan view of the embodiment of FIG. 6; and

FIG. 10 is a bottom perspective view of the embodiment of FIG. 6.

We claim:

The ornamental design for closure for a display package, as shown and described.
